UNITED STATES PATENT OFFICE.

JAMES EMANUEL DE LAMAR, OF DALARK, ARKANSAS.

AUTOMATIC ROAD-GATE.

SPECIFICATION forming part of Letters Patent No. 691,363, dated January 21, 1902.

Application filed June 8, 1901. Serial No. 63,735. (No model.)

To all whom it may concern:

Be it known that I, JAMES EMANUEL DE LAMAR, a citizen of the United States, residing at Dalark, in the county of Dallas and State of Arkansas, have invented certain new and useful Improvements in Automatic Road-Gates; and I do hereby declare the following to be a full, clear, and exact description of the invention, such as will enable others skilled in the art to which it appertains to make and use the same.

My invention is an automatic farm-gate; and it consists of means for automatically opening and closing and latching and unlatching said gate.

In the accompanying drawings, Figure 1 is a perspective view of my invention with the gate closed. Fig. 2 is a top view of the plate, pulleys, and ropes used to operate the gate, the top plate being removed.

My invention is described as follows:

1 represents aprons which cover part of the roadway, lie flat on the ground, and are secured in place. Rising from one end of each of these aprons is an upright post 2, and extending inwardly from the top ends of said posts are braced arms 3. These arms extend to about the center of the roadway and have depending from their free ends pulleys 4. The aprons 1 are provided with slots 5 near the posts. Journaled in the woodwork on which said aprons rest are cylinders 6, and rising perpendicularly from said cylinders and rigidly secured thereto are pedals 7. These pedals may turn forward or backward, and rigidly secured to the outer ends of the cylinders 6 are levers 8. Secured to the inner faces of the posts 2 are pulleys 9. Situated on the aprons 1 and beyond the pedals 7, reckoning from the gate, are cone-shaped spiral springs 10, and when the pedals 7 are pressed down on said springs they (said springs) are pressed down flat, and when the pressure is removed the springs throw the pedals and the levers into an upright position or a little beyond an upright position.

11 is the rear gate-post, to which the gate is hinged.

12 represents braces.

13 represents stop-posts to stop the gate when it is swung back on a line with the road-

14 represents beams attached to the braces 12 and stop-posts 13, each having on its outer end latch-holders 15.

55

16 represents the rear perpendicular rails of the gate. 17 represents the front perpendicular rails of the gate. Secured between these rails 16 and 17 are horizontal bars 18.

60

19 represents braces.

20 is the latch-post, and on the inner face of the latch-post is secured a latch-keeper.

Secured to the upper ends of the perpendicular slats 16 and to braces 26 is a frame 27, in which are horizontally secured pulleys 28, 65 and to the upper bar 18 of the gate is pivoted a right-angle triangle lever 29. To the forward end of this lever are pivoted two upright bars 30. To the lower end of these levers 30 is pivoted the free end of a latch 31. 70 The rear end of the latch is pivoted between the braces 19, and to the forward end of the latch 31 is secured a double catch 32, one end extending from one side of the latch and the other to the other side of the latch. This 75 latch is held down by a spring.

Secured to the free end of one of the levers 8 is a cord 33, which passes over pulley 9, around pulleys 28, and is then secured to one end of a rod 34, the other end of said rod being secured to the upper end of the right-angle triangle lever 29. Secured to the free end of the opposite lever 8 is a cord 35, which passes up over pulley 9, around pulleys 28, and is secured to one end of the said rod 34, 85 the other end of which rod is secured to the upper end of right-angle lever 29. These cords are crossed between the pulleys 28, so that when I pull on either one of the cords the gate is thrown from me.

90

The operation of the gate is as follows: When a vehicle approaches the gate in the direction of the arrow 36, one of the front wheels strikes the pedal 7 and throws the arm 8 forward to the ground, thus pulling on the 95 cord 33, bringing the rear end of the frame 27 in the direction of the arrow 37, raising the latch 31, and throwing the gate open, which swings back, the cross-catch 32 catching over the latch-catch 15. When the vehicle passes through the gateway, it throws the other pedal 7 outwardly until it strikes the spring 10, thus throwing the rod 8 outwardly until it comes nearly to the ground, or, say,

100

about one-eighth of a circle from the ground. This operation raises the cross-catch 32 off of the catch 15 and swings the gate shut, the latch 32 sliding up the incline of the latch-holder 25 and dropping into the notch. As the lever 8 just mentioned does not fall quite to the ground, it only raises the cross-catch high enough to escape the catch-holder 15, and as it takes a full quarter-turn to raise the latch 31 out of the latch-holder 25 the hind wheel of the vehicle does not reopen the gate as it passes over the pedal 7. After the wheels pass over the pedals the springs 10 throw them and the rods 8 up. When the vehicle comes from the other direction, the operation is just the same, except that the motions are reversed. If at any time the pedals should get out of order and inoperative, then I may release the ropes from the arms 8 and pulleys 9 and carry them over pulleys 4, thus operating the gate by hand, and I claim the right to manufacture the gate without the automatic opening and closing device.

Having described my invention, what I claim as new, and desire to secure by Letters Patent, is—

1. The combination of a swinging gate adapted to be opened and shut by cords attached to suitable mechanism; aprons, one on each side of the gate secured over part of the roadway and provided with slots; cylinders journaled immediately under said slots and protruding slightly above the same; cone-shaped coil-springs, one secured on the upper face of each apron; pedals, one rigidly secured to each cylinder, said pedals adapted to be pressed inwardly to the ground, or outwardly onto the said coil-springs; levers, one rigidly secured to each cylinder, their free ends moving up and down with the pedals; posts, one rising from the outer end of each apron; pulleys secured to the inner faces of said posts; cords secured to the free ends of said levers, passing over said pulleys, thence around and crossing between rollers secured in a frame on the upper end and rear part of the gate, thence secured to mechanism adapted to raise the gate-latch and catches, substantially as shown and described and for the purposes set forth.

2. The combination of a swinging gate adapted to be opened and shut by cords attached to suitable mechanism; aprons, one on each side of the gate, secured over part of the roadway and provided with slots; cylinders

journaled immediately under said slots and protruding slightly above the same; cone-shaped coil-springs, one secured on the upper face of each apron; pedals, one rigidly secured to each cylinder, said pedals adapted to be pressed inwardly to the ground, or outwardly onto the said coil-springs; levers, one rigidly secured to each cylinder, their free ends moving up and down with the pedals; posts, one rising from the outer end of each apron; pulleys, secured to the inner faces of said posts; cords, secured to the free ends of said levers, passing over said pulleys, thence around and crossing between rollers secured in a frame on the upper end and rear part of the gate, thence secured to a rod pivoted to a right-angle triangular lever, pivoted to the gate; said lever adapted to operate a latch provided with cross-catches, substantially as shown and described and for the purposes set forth.

3. The combination of a swinging gate adapted to be opened and shut by cords attached to suitable mechanism; aprons, one on each side of the gate, secured over part of the roadway and provided with slots; cylinders journaled immediately under said slots and protruding slightly above the same; cone-shaped coil-springs, one secured on the upper face of each apron; pedals, one rigidly secured to each cylinder, said pedals adapted to be pressed inwardly to the ground, or outwardly onto the said coil-springs; levers, one rigidly secured to each cylinder, their free ends moving up and down with the pedals; posts, one rising from the outer end of each apron; pulleys secured to the inner faces of said posts; cords secured to the free ends of said levers, passing over said pulleys, thence around and crossing between rollers secured in a frame on the upper end and rear part of the gate, thence secured to a rod pivoted to a right-angle triangular lever pivoted to the gate; said lever adapted to operate a latch provided with cross-catches, substantially as shown and described and for the purposes set forth.

In testimony whereof I affix my signature in presence of two witnesses.

JAMES EMANUEL DE LAMAR.
